US00D845287S

(12) **United States Design Patent** (10) **Patent No.:** **US D845,287 S**
(45) **Date of Patent:** **** Apr. 9, 2019**

(54) **MOBILE PHONE**

(71) **Applicant:** **Samsung Electronics Co., Ltd.**,
Suwon-si (KR)

(72) **Inventors:** **Jiyoung Lee**, Seoul (KR); **Kwangmoon Kim**, Seoul (KR); **Kukhwan Kim**, Seoul (KR); **Hae Sung Park**, Seoul (KR); **Dahyun Lee**, Seoul (KR); **Miri Lee**, Namyangju-si (KR); **Jin-Hoo Lee**, Seoul (KR); **Youngsang Jang**, Anyang-si (KR); **Woohyeok Jeong**, Seoul (KR)

(73) **Assignee:** **SAMSUNG ELECTRONICS CO., LTD.**, Suwon-si (KR)

(**) **Term:** **15 Years**

(21) **Appl. No.:** **29/625,124**

(22) **Filed:** **Nov. 7, 2017**

(30) **Foreign Application Priority Data**

Jun. 1, 2017 (KR) 30-2017-0025030

(51) **LOC (11) Cl.** **14-03**

(52) **U.S. Cl.**

(57) **CLAIM**

The ornamental design for a mobile phone, as shown and described.

DESCRIPTION

FIG. 1 is a front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly dashed broken lines in the drawings illustrate portions of the mobile phone that form no part of the claimed design. The dot-dash broken lines in the drawings represent the bounds of the claim and form no part of the claimed design.

1 Claim, 5 Drawing Sheets
